F. J. BRUMME,
AUTOMATIC GOVERNOR,
APPLICATION FILED MAR. 8, 1920.

1,343,808.

Patented June 15, 1920.

FIG. 1

FIG. 2

UNITED STATES PATENT OFFICE.

FRANK J. BRUMME, OF COOKSVILLE, ILLINOIS.

AUTOMATIC GOVERNOR.

1,343,808.

Specification of Letters Patent. Patented June 15, 1920.

Application filed March 8, 1920. Serial No. 364,092.

To all whom it may concern:

Be it known that I, FRANK J. BRUMME, a citizen of the United States, and a resident of Cooksville, in the county of McLean and State of Illinois, have invented a new and useful Improvement in Automatic Governors, of which the following is a full, clear, and exact description.

My invention relates to improvements in automatic governors, and it consists in the combinations, constructions, and arrangements herein described and claimed.

An object of my invention is to provide an automatic governor designed to be attached to certain portions of an internal combustion engine and actuated by the operation thereof, whereby the flow of fuel through the carburetor in such internal combustion engine is automatically controlled.

20 A further object of my invention is to provide a device of the type described that can be adjusted at will while the engine is in motion, whereby the rate of speed which will be uniformly maintained can be varied.

25 A further object of my invention is to provide a device of the type described that is compact in form and takes up little space, thereby permitting the same to be installed between the fan and the radiator in a cooling system of an internal combustion engine of ordinary construction.

30 A further object of my invention is to provide a device of the type described that is relatively simple in construction and operation and is not liable to get out of order easily.

35 Other objects and advantages will appear in the following specification, and the novel features of the invention will be particularly pointed out in the appended claims.

40 My invention is illustrated in the accompanying drawings, forming part of this application, in which—

45 Figure 1 is a diagrammatic view of an internal combustion engine of a well known type showing the device applied,

Fig. 2 is an enlarged longitudinal sectional view of a portion of the device,

50 Fig. 3 is an end view of the mechanism shown in Fig. 2,

Fig. 4 is an enlarged longitudinal sectional view of a portion of a modified form of the device.

While in the accompanying drawings I

have shown the device applied to an internal 55 combustion engine of a Ford type, it is to be understood that the device can be used with any internal combustion engine of a standard construction.

In carrying out my invention, I make use 60 of an internal combustion engine 1, which is provided with an intake manifold 2 and a carburetor 3. A suitable support 4 is secured to the engine and has an enlarged top portion 5 provided with a bore 6 in which 65 is rigidly mounted a sleeve 7. The sleeve 7 has a central bore 8 in which a stub shaft 9 is slidably disposed. A pulley 10 is rotatably mounted upon the sleeve 7, and is maintained thereon by means of a flange 11 70 at the end of the sleeve 7. The flange 11, it will be noted, is received within an annular recess 12 in the end of the pulley 10.

The pulley 10 is secured at 13 to a body portion 14 of a fan which has a plurality 75 of blades 15. It will be understood that the fan is operated by the operation of the pulley 10.

A housing 16 is secured to opposite blades 15 of the fan and is arranged to be rotated 80 therewith. Lugs 17 project within the housing 16. A pair of L-shaped rods 19 are pivotally fastened at 18 to the lugs 17. Each of the L-shaped rods 19 carries a weight or ball 20 at the end of one arm and has its 85 other arm extending toward a corresponding arm of the other L-shaped rod and in contact with a thrust ring 21 which is mounted upon a thrust bearing 22. The latter is rigidly secured to an end of the shaft 9. 90 Anti-friction bearings 23 are provided between the thrust ring 21 and the thrust bearing 22.

The support 4 has a vertical extension 24 provided with a notch 26 adapted to receive 95 the end of a spring 25. The latter has its other end fastened at 27 to an arm of an L-shaped lever 28 which is pivotally fastened at 29 to the casing of the engine 1, whereby the arm of the lever 28 is held against the 100 adjacent end of the stub shaft 9, thus holding the thrust member carried at the other end of the stub shaft 9 in contact with the rods 19 which carry the weights or balls 20. The other end of the L-shaped lever 28 is 105 pivotally fastened at 30 to one end of a vertical arm 31.

A pin 32 projects laterally from the other

end of the arm 31 and is slidably disposed within a slot 33 provided in the carbureter 3. The pin 32 is operatively connected to the fuel control valve (not shown) within 5 the carbureter 3.

An additional arm 34 is connected at 35 to the arm 31 and has one end slidably disposed within a suitable support 36. The other end of the arm 34 is pivotally connected at 37 to a lever 38 which is in turn pivoted at 39 to a casing of the engine or to any other suitable support. An arm 41 is pivotally fastened at 40 to the lever 38. The arm 41 may be connected to members (not 15 shown) leading to the driver's seat in an automobile in which the engine 1 is installed and can be operated by the driver while the engine 1 is in operation.

From the foregoing description of the 20 various parts of the device, the operation thereof may be readily understood. The pulley 10 is operated by a belt 42 which is engaged by a moving part which is preferably actuated by a member mounted upon 25 a crank shaft associated with the engine 1. The pulley 10 in turning, operates the fan blades 15 which in turn impart a rotary movement to the housing 16. When the housing 16 is rotated at a predetermined 30 speed, the weights or balls 20 carried by the L-shaped rods 19 will move outwardly or away from each other, thus exerting a pressure against the thrust ring 21 and slidably moving the stub shaft 9 against the tension 35 of the spring 25. The lever 28 will therefore be moved and the pin 32 will be slidably moved in the slot 33, thus operating the valve in the carbureter and reducing the flow of fuel through the carbureter thereby 40 reducing the speed of the engine. It will be obvious that a desired speed will be uniformly maintained. The speed which will be uniformly maintained can be varied at will by means of the arm 41 which is oper- 45 able from the driver's seat, since movement of the arm 41 will impart a corresponding movement to the arm 31 and the control valve within the carbureter will be set to permit the flow of a larger or smaller quan- 50 tity of fuel through the carbureter as it is desired to increase or lower the speed to be uniformly maintained.

Referring now to Fig. 4, it will be noted that I show a portion of a modified form 55 of the device. The construction of this form of device is identical with the form described with the exceptions about to be set forth and I have accordingly indicated corresponding parts in the two forms of the device by the 60 same reference numerals. The sleeve 7 is rigidly mounted within the enlarged top portion 5 of the support 4, and the pulley 10 is rotatably mounted upon the sleeve 7 in the manner described. The pulley 10 oper- 65 ates the fan blades 15 which in turn rotate

the housing 16. The latter is secured to the fan blades 15 in the manner previously described. Instead of the single stub shaft 9 in the embodiment of the invention, illustrated in Figs. 1 and 2, it will be noted that I provide two separate stub shafts 50 and 51. The stub shaft 51 has a disk 52 at its end. Each of the levers 19 has an arm in frictional contact with the disk 52. A ball bearing 53 is disposed between the adjacent 70 ends of the shafts 50 and 51. Consequently, when the weights 20 and 21 move outwardly or away from each other, the stub shaft 51 will be slidably moved within the sleeve 7 and will push the bearing 53 and the shaft 80 50 before it, thus operating the lever and link device operatively connected with the valve in the carbureter in the manner set forth in the description of the preferred form of the device.

It will be noted that the shaft 51 will revolve with the housing 16 since the arms of the levers 19 are in frictional contact with the disk 52 which is carried at the end of the shaft 51.

It is obvious that a desired speed will be maintained when the device is used. One of the main advantages of the device is that the provision of the lever and link device, operable by the driver of an automobile, 95 permits a quick change in speed while the engine is in operation and the automatic governor will then maintain the speed at the rate set.

I claim:

1. An internal combustion engine, having a valve, a support, a sleeve rigidly mounted in said support and projecting therefrom for a portion of its length, a pulley mounted to rotate upon said sleeve, a fan secured 105 to said pulley and arranged to rotate therewith, a housing carried by said fan to rotate therewith, a pair of opposite centrifugal members carried on the inside of said housing, each of said centrifugal members having 110 an arm extending toward a corresponding arm of the other centrifugal member, a stub shaft slidably disposed in a central bore of said sleeve and having one end extending within said housing, a thrust bearing carried upon the end of said stub shaft extending within the housing, an L-shaped lever pivotally secured to said engine and having an arm arranged to press against the adjacent end of said stub shaft, a tension spring 115 connecting said support and the arm of said L-shaped lever pressing against the end of said stub shaft, whereby the thrust bearing upon said stub shaft is maintained against the arms of the centrifugal mem- 120 bers, a link connecting said lever and the valve in said carbureter, whereby said valve is controlled by the operation of the centrifugal members, and an additional lever and link device connected to the valve in the 125 130

carbureter whereby the flow of fuel therethrough can be regulated at will while the engine is in operation.

2. In an internal combustion engine a carbureter having a valve, a support, a sleeve rigidly mounted in said support and having a portion of its length projecting therefrom, a pulley mounted to rotate on the projecting portion of said sleeve, means for operating said pulley, a fan carried by said pulley and arranged to rotate therewith, a housing secured to said fan to be rotated therewith, a pair of opposite centrifugal members carried upon the inside of said housing and operated when said housing is rotated at a predetermined speed, a stub shaft slidably disposed within said housing, said end being maintained in contact with said centrifugal members, a second stub shaft having one end slidably disposed within said sleeve, said last named stub shaft being co-axially alined with said first named stub shaft, a bearing between the adjacent ends of said first named stub shaft and said second named stub shaft, a lever and link connection between the second named stub shaft and the valve in said carbureter, said lever and link connection being maintained in position by the action of a tension spring arranged to hold the lever in contact with the end of said second named stub shaft, whereby said valve in the carbureter is operated by a longitudinal movement of said first named stub shaft, said longitudinal movement being occasioned by the operation of said centrifugal member, and an additional lever and link device secured to the valve of said carbureter and operable while the internal combustion engine is in motion for regulating the flow of fuel through said carbureter and thereby changing the rate of speed of said engine.

3. In an internal combustion engine, a carbureter having a valve, a fan, means for

operating the fan, a housing secured to said fan to rotate therewith, a pair of opposite centrifugal members carried within the housing and operated when the fan is rotated at a predetermined speed, a support, a sleeve mounted in said support, a stub shaft slidably disposed in said sleeve, a thrust bearing carried at one end of said stub shaft, said thrust bearing being positioned in contact with said centrifugal members whereby said stub shaft is moved in a longitudinal direction by the operation of said centrifugal members, means arranged between the opposite end of said stub shaft and the valve in said carbureter for controlling said valve, said last named means being operated when said stub shaft is moved in a longitudinal direction, and manually operable means for adjusting the valve in the carbureter at will.

4. In an internal combustion engine, a carbureter having a valve, a fan, means for operating the fan, a housing secured to said fan to rotate therewith, a pair of opposite centrifugal members carried within the housing and operated when the fan is rotated at a predetermined speed, a support, a sleeve mounted in said support, a stub shaft slidably disposed in said sleeve, a thrust bearing carried at one end of said stub shaft, said thrust bearing being positioned in contact with said centrifugal members whereby said stub shaft is moved in a longitudinal direction by the operation of said centrifugal members, a lever and link device arranged between the opposite end of said stub shaft and a valve in said carbureter for controlling said valve, said lever and link device being operated by the stub shaft when the latter is moved in a longitudinal direction, and manually operable means for adjusting the valve in the carbureter at will.

FRANK J. BRUMME.
